UNITED STATES PATENT OFFICE.

GIOVANNI EMANUELE ELIA, OF PARIS, FRANCE.

SHIP OR VESSEL.

1,000,903.

Specification of Letters Patent. Patented Aug. 15, 1911.

Original application filed June 22, 1910, Serial No. 563,304. Divided and this application filed June 2, 1911. Serial No. 630,826.

To all whom it may concern:

Be it known that I, GIOVANNI EMANUELE ELIA, a subject of the King of Italy, and resident of Hôtel de Crillon, Place de la Concorde, Paris, in the Republic of France, have invented certain new and useful Improvements in Ships or Vessels, of which the following is a specification.

This application is a divisional application of the one filed by me on the 22nd of June, 1910, Serial No. 563,304.

The invention relates to ships or vessels and is particularly applicable for use in connection with vessels employed in naval warfare, the object being to preserve the stability of the same in the event of their being subjected to the effects of a submarine explosion.

It has heretofore been proposed to provide a ship with thin outer plating and strong inner plating divided by partitions into a certain number of water tight compartments in each of which there is arranged a system of wire cables for the purpose of absorbing or neutralizing the effects of a submarine explosion. This arrangement while very effective against the explosion of torpedoes or submarine mines, which affect a comparatively small portion of the ship, does not present sufficient protection against the explosion of cables or explosives arranged in the form of a belt and extending the whole length of the ship. In this case the explosion of such a cable on one side of the ship would rupture the whole of that side with the result that water would enter the aforesaid compartments thereby destroying the balance of the ship and causing the same to heel over to such an extent that it would become filled with water and sink.

According to this invention each of the water tight compartments is provided with a balance or displacement preserving device which can assume after the explosion a volume which is substantially equal to that of the corresponding watertight compartment with the object of preserving for each compartment substantially its original volume after the outer plating has been broken away with the result that the balance and displacement of the ship will remain the same.

In order that the said invention may be clearly understood and readily carried into

effect I will describe the same more fully with reference to the accompanying drawings in which:

Figure 1 is a cross section of part of a ship provided with a balance and displacement preserving device in accordance with this invention. Fig. 2 is a view of part of Fig. 1 drawn to a larger scale.

The sides of the ship are divided in the known manner into watertight compartments, the longitudinal walls of which are constituted by thin outer plating *a* and by strong inner plating *c* protected by a framework or system of steel cables *b* arranged behind the plating *a*.

The balance or displacement preserving device comprises a flexible envelop *e* capable of being folded into a small space behind a protecting plate *f* which is hinged to the support for the cables *b* or to any other suitable part of the ship's hull. Situated in the envelop *e* are two easily broken receptacles *g* and *h* drawn on a larger scale in Fig. 2, containing substances capable upon mixing with water of generating sufficient gas to inflate the envelop *e* to an extent that is substantially equal to the volume of the compartment in which the envelop is situated. Any suitable substance may be employed for generating gas in the envelop *e* when the ship's side is subjected to the effects of a submarine explosion. For example, water may be placed in the receptacle *g* and carbide of calcium in the receptacle *h*.

The outer plating *a* is preferably constituted of hard and brittle steel which will break up into small fragments under the influence of a shock without being forced into the interior of the ship. When the aforesaid plating is destroyed by the effects of an explosion, the shock ruptures the two receptacles *g* and *h*. The contents of these receptacles then become mixed and a certain quantity of acetylene gas is generated which inflates the envelop *e* and causes it to fill its compartment and to force the system of cables *b* outwardly so that they practically take the place of the destroyed plating *a*.

The details of construction can be variously modified without departing from the nature of the invention. For example the receptacle *e* shown in Figs. 1 and 2 may be constructed of any appropriate material

such as rubbered fabric, leather, oilcloth or any other impermeable substance possessing the necessary amount of strength.

Having now particularly described and ascertained the nature of my said invention and in what manner the same is to be performed, I declare that what I claim is:

1. In a ship's hull of the kind set forth, the combination of water-tight compartments, of a system of steel cables inside the compartments, and a balance or displacement preserving device situated in each of the aforesaid compartments, comprising a flexible envelop, a protecting plate in front 15 of the said envelop, two easily broken receptacles in the envelop, a substance in the receptacles, of such a nature that when mixed with the water at the moment of an

explosion, gas is generated in sufficient quantity to inflate the envelop for the purpose 20 specified.

2. In a ship's hull of the kind set forth, the combination of water-tight compartments, of a balance or displacement preserving device in each compartment in combination 25 with steel cables inside the compartments, acting as a preserving medium for the said compartments at the moment of an explosion.

In testimony whereof I have hereunto 30 placed my hand, at Marseille France this fifteenth day of May 1911.

GIOVANNI EMANUELE ELIA.

In the presence of two witnesses—

ALLAN MACFARLANE,
PAUL H. GANS.
